UNITED STATES PATENT OFFICE.

ALVA S. LOOMIS, OF MENOMONEE FALLS, WISCONSIN, ASSIGNOR OF ONE-HALF TO
ERNEST C. KAMBE, OF MENOMONEE FALLS, WISCONSIN.

ADJUSTABLE SPOT-LIGHT FOR MOTOR-VEHICLES.

1,317,170.

Specification of Letters Patent. Patented Sept. 30, 1919.

Application filed April 19, 1919. Serial No. 291,217.

To all whom it may concern:

Be it known that I, ALVA S. LOOMIS, a citizen of the United States, and resident of Menomonee Falls, in the county of Waukesha and State of Wisconsin, have invented new and useful Improvements in Adjustable Spot-Lights for Motor-Vehicles, of which the following is a description, reference being had to the accompanying drawings, which are a part of this specification.

The present invention relates to certain new and useful improvements in spot lights for motor cars, and has for its primary object to provide a spot light which can be readily moved in any direction to throw the beam of light along the road.

A further object of this invention is to provide a spot light which is especially adapted for use on trouble cars for repairing electrical or telephone wires, in that the spot light may be readily moved to throw the beam of light at all angles.

A further object of this invention is to provide a spot light capable of use with any style of vehicle and which will not disfigure the vehicle and which will be efficient in its operation.

With the above and other objects in view, which will appear as the description proceeds, my invention resides in the novel construction, combination and arrangement of parts substantially as hereinafter described, and more particularly defined by the appended claims, it being understood that such changes in the precise embodiment of the hereindisclosed invention may be made as come within the scope of the claims.

In the accompanying drawing I have illustrated one complete example of the physical embodiment of my invention constructed according to the best mode I have so far devised for the practical application of the principles thereof, in which:

Figure 1 is a perspective view of a portion of an automobile with my invention embodied therein;

Fig. 2 is a top plan view of my invention;

Fig. 3 is a sectional view taken on the line 3-3 of Fig. 2;

Fig. 4 is a view, part in section and part in elevation, said view being taken on the line 4-4 of Fig. 2;

Fig. 5 is a sectional view taken on the line 5-5 of Fig. 4;

Fig. 6 is a view, part in section and part

in elevation, said view being taken on the line 6-6 of Fig. 2; and

Fig. 7 is a sectional view taken on the line 7-7 of Fig. 2.

Referring now more particularly to the drawing, 5 designates an automobile, to the dashboard of which is secured a pair of bracket members 6 in which the rod members 7 and 8, and coöperating spot light 9 are mounted. While in the present embodiment, the rod members 7 and 8 are illustrated as being horizontally disposed, it will be understood that they may be disposed vertically without affecting the operation thereof.

Each member 6 has journally retained therein by means of inwardly projecting flanges 10 a spool member 11 provided with an opening 12 shaped to receive the rods 7 and 8. The brackets 6 are secured to the machine 5 by means of screws 13, the innermost screw 13 serving to retain the ends 14 of the brackets 6 in closed position.

The rods 7 and 8 are U-shaped in cross section, and have their inner faces meeting as at 15. The rod 8 is substantially retained in the spool members 6 against lateral movement by means of lugs 8' secured to the rod 8 and engaging the spool member, as best shown in Fig. 5, and the rod member 7 is free to move laterally in the spool members 11 for the reasons hereinafter described.

The spot light 9 has its base 9' pivoted in a lug 16 secured to the rod 8 by screw 16', and has fixed to its base 9' one end 17 of an arm 18, the outer end of which is slotted as at 19 for engaging with stud 20, carried by rod member 7. By this arrangement, when the rod 7 is moved laterally with respect to rod 8, the spot light 9 will be turned on its pivot as depicted by dotted lines in Fig. 2.

For moving the rod member 7, as just described, a handle or lever 21 is provided, having its inner end pivoted as at 23 for pivotal engagement with a stud 24 carried by a projection 25 secured to rod member 7 by means of suitable fastenings 26.

From the foregoing description taken in connection with the drawings, it will be readily seen that to move the spot light 9 to shew the beam of light vertically, it is simply necessary to raise the lever handle 21 which will rotate the rods 7 and 8 in their brackets, as depicted by dotted lines 110

in Fig. 3, and when it is desired to move the beam of light horizontally, the handle 21 is moved laterally in the direction in which it is desired to throw the light, this 5 operation moving the rod 7 laterally in the spool members 11 and revolves spot light 9 on its pivot by means of its arm 18, as hereinbefore described.

While in the drawing I have illustrated 10 this invention as in use with only one spot light it will be understood that the rod members 7 and 8 may be extended so as to provide a spot light on each side of the machine.

15 What I claim as my invention is:

1. A device of the class described, comprising, a bracket adapted to be secured to a support, a bearing member rotatably carried by said bracket, a rod member rigidly 20 mounted in said bearing member, a second rod member slidably mounted in said bearing member, a spot light carried by one of said rod members, a coupling between the spot light and the other of said rod members, and means for operating the rod members to move the spot light in all directions.

2. A device of the character described, comprising, a bracket adapted to be carried by a support, a bearing member, rotatably 25 mounted in said bracket, a rod member rigidly mounted in said bearing member, a second rod slidably mounted in said bearing member, a spot light pivoted to one of said rod members, link means pivotally connecting the pivot of the spot light with the other of said rod members, and a handle having its inner end pivoted to the first mentioned rod member and its intermediate portion slidably pivoted to the last mentioned rod 30 member for moving the rod members to swing the spot light in all directions.

3. A device of the class described, comprising, a bracket member and rod member carried thereby and capable of rotation but held against longitudinal movement, a second rod member carried by said bracket member and capable of rotation and also adapted to be moved longitudinally, a spot light pivotally carried by one of said rod 45 members, means connecting the spot light

with the other rod member, and means for rotating said rod members and moving the second rod member longitudinally to swing the spot light in all directions, said means including an operating handle having one 55 end pivoted to said first mentioned rod member and provided with an elongated slot at a point spaced from its pivoted end and adapted to pivotally engage a stud carried by said second rod member.

4. In a device of the character described, the combination with a support, of bracket members carried thereby, a spool member rotatively mounted in each bracket, a rod member rigidly carried by the spool members, a second rod member slidably mounted in said spool members, a spot light pivotally carried by one of said rod members, an arm carried by the pivot of said spot light and having its free end slidably pivoted to the 60 other of said rod members, and an operating handle engageable with said rod members to swing the spot light in all directions.

5. In a device of the class described, the combination with a support, of a securing 65 collar rotatably carried by the support, a pair of complementary rod members mounted in said securing collar, one of said rod members being free to move longitudinally in said securing collar and both of said rod 70 members being capable of rotation with said securing collar, and a spot light connected with said rod members, and means for operating said rod members to move the spot light in all directions.

6. In a device of the class described, the combination with a support, of a pair of rod members, a bracket member carried by said support, a securing collar rotatably mounted in said bracket member, one of said 75 rod members being fixed in said securing collar and the other rod member being slidably mounted therein, a spot light pivotally carried by one of said rod members, means connecting the spot light with the other of 80 said rod members, and means for moving said rod members to swing the spot light in all directions.

In testimony whereof I affix my signature.
ALVA S. LOOMIS.
